UNITED STATES PATENT OFFICE

109,702

DESIGN FOR A COAT

Samuel H. Dick, New York, N. Y.

Application April 13, 1938, Serial No. 76,465

Term of patent 3½ years

To all whom it may concern:

Be it known that I, Samuel H. Dick, a citizen of the United States and residing in Manhattan, in the city, county, and State of New York, have invented a new, original, and ornamental Design for a Coat, of which the following is a specification, reference being had to the accompanying drawing, forming part thereof.

Fig. 1 is a front view of a coat showing my new design.

Fig. 2 is a rear view thereof.

The flower at the shoulder of the coat is permanently attached.

The characteristic feature of my design resides in the specific sleeves in association with the folds on the front neck portion in combination with the specific coat, as shown.

I claim:

The ornamental design for a coat, substantially as shown and described.

SAMUEL H. DICK.
